UNITED STATES PATENT OFFICE.

AUGUST N. RITZ, OF MILWAUKEE, WISCONSIN.

DESIGN FOR A PASTE-JAR.

SPECIFICATION forming part of Design No. 31,181, dated July 11, 1899.

Application filed June 12, 1899. Serial No. 720,306. Term of patent 14 years.

To all whom it may concern:

Be it known that I, AUGUST N. RITZ, a citizen of the United States, residing at Milwaukee, in the county of Milwaukee and State of Wisconsin, have invented and produced a new and original Design for Paste-Jars; and I do hereby declare the following to be a full, clear, and exact description of the same, reference being had to the accompanying drawings, 10 forming a part thereof.

In the said drawings, Figure 1 is a view in side elevation; Fig. 2, a vertical sectional view on the line 2 2 of Fig. 3, and Fig. 3 a plan view of a paste-jar embodying my new 15 design.

My design relates to the new and original shape or configuration of the article.

The leading or essential feature consists in the unitary design for a paste-jar made the 20 subject of illustration, comprising the shape of the outer cylindrical wall A, horizontal bottom B, and inner partition C, which latter is of generally semicircular form and of less height than that of the outer wall A, to 25 which it is joined. The partition C rises ver-

tically from the bottom B, and the inner or concave face of said partition gradually tapers or converges away from the adjacent portion of the wall A, and the outer or convex face of said partition C first curves inward from the bottom toward the concave face and then as it rises curves or flares outward to the top, and the said partition is very considerably thicker at its base than at its top. 30

Minor features of this design comprise a 35 slight inward and downward taper of the inner surface of the cylindrical outer wall A and the horizontal exterior annular ribs D D.

Having thus described my invention, what I claim as new, and desire to secure by Letters 40 Patent, is—

The design for a paste-jar substantially as herein shown and described.

In testimony whereof I affix my signature in presence of two witnesses.

AUGUST N. RITZ.
